BROODER FOR CHICKS

Frank P. Crandon, New Bedford, Mass.

Application February 7, 1931, Serial No. 514,083

1 Claim. (Cl. 119—34)

My invention relates to brooders for chicks and it has for its object to improve the construction and mode of operation of devices of this class. This invention also has for its object to provide an improved brooder system including a house within which is arranged a heated hover of improved construction.

To these ends I have provided a brooder system of that class which includes a house within which is provided a hover supported adjacent the floor of the structure, and within which hover is arranged a radiator whose inlet is connected by a supply conduit with the outlet of a water heater, and whose outlet is connected with the inlet of said water heater by a return conduit.

These elements have heretofore been associated in systems of this kind but a feature of novelty of my new system consists in incorporating a portion of the return conduit within the floor of the hover below the level of the top surface thereof, but closely adjacent the latter, so that the hover floor is heated as well as the hover itself and the interior of the latter.

In the best form of my invention the floor of the hover is a monolith made from concrete and the portion of the return conduit that is incorporated therein is embedded within the material of this concrete floor so that it is in intimate contact therewith and transmits its heat directly to the same. Preferably a blanket of heat insulating material such as sheet asbestos is arranged close to and directly below this portion of the return conduit which confines the heat to the top portion of the floor of the hover and prevents its being dissipated downwardly.

Also in the best form of my invention the portion of the return conduit that is directly below the hover, and which forms part of the floor thereof, is constructed with a plurality of branches disposed in a horizontal plane and constituting a laterally extending radiator which heats all parts of the floor beneath the hover.

It is also a feature of my invention that the hover includes, as a part thereof, a canopy body portion, preferably made from sheet metal, provided interiorly with a horizontal partition which may rest upon the top of the radiator thereby at times to utilize the latter as a support for said canopy body to which heat is transmitted directly from the radiator.

It is also a feature of my invention that this partition includes a bottom layer of sheet metal and an upper layer of heat insulating material, such as asbestos, so that most of the heat received by the partition from the radiator is re-

flected downwardly on to the chicks instead of being transmitted, or permitted to radiate, upwardly as heretofore.

Other features of my invention are hereinafter pointed out.

In the accompanying drawings:—

Figure 1 illustrates a brooder system constructed in accordance with my invention.

Figure 2 is a central vertical sectional view of the hover including a portion of the floor of the latter.

Figure 3 is a plan view of a portion of the return conduit showing also the radiator which constitutes part of the floor of the hover, and the blanket of insulating material beneath the radiator the concrete of the floor being omitted.

My improved brooder system as herein illustrated includes a house or apartment the floor of which is made from concrete and is shown at 1; the roof at 2; an end wall at 3, and a side wall at 4.

Seated upon the floor 1 is an upstanding radiator that is indicated generally at 5, said radiator being of that type which comprises two manifolds 6 and 7 connected by a row or series of straight parallel pipes 8. These pipes 8 are disposed vertically all in one vertical plane so that the radiator as a whole occupies a minimum of floor space.

The inlet of the radiator 5 is connected by a supply conduit 10 with the outlet of a water heater 11 whose inlet is connected by a return conduit 12 with the outlet of the radiator 5. The supply conduit 10 is arranged above the level of the return conduit 12 and consequently hot water will circulate from heater 11 through conduit 10 to radiator 5 and thence back to heater 11 again through return conduit 12.

The hover of the system is indicated generally at 9 and includes as a part thereof a conical sheet metal canopy body 13 provided, as usual, with a pendant felt or fabric skirt 14 that is slitted to facilitate the entrance and exit of chicks. Intermediate the upper and lower ends thereof the sheet metal canopy body 13 is made with a horizontal partition that is indicated generally at 15 and which includes as a part thereof a sheet metal bottom wall 16 whose top side is covered with a layer of heat insulating material 17, such as asbestos.

The partition 15 is made at its middle with an aperture communicating with the lower end of a flue 18 which is joined to the sheet metal wall 16 of said partition. This flue 18 extends upwardly through the top of the sheet metal body

13 to which it is fastened near its upper end. The upper end of the flue 18 is provided with a damper 19 pivotally connected near its middle to one arm of a lever 20 that is fulcrumed at 21 5 on the canopy body 13. This lever 20 is connected by a stem 22 with a thermostatic regulator 23 fastened to a bracket 24 projecting from the canopy body 13. The thermostatic regulator 23 is within the hover 9 and operates as usual to 10 automatically adjust lever 20 and damper 19 so as to maintain the temperature within the hover 15 at or near a predetermined point.

As shown in Figure 2 the partition 15 and flue 18 provide an annular dead-air space 25 within 15 the upper end portion of the canopy body 13 and this dead-air space serves to insulate the partition 15 from the upper portion of the body 13. Also, the top asbestos layer 17 of the partition 15 prevents upward radiation of heat from 20 the sheet metal wall 16 of the partition and also prevents the transmission of heat directly from 25 said sheet metal wall 16 to the dead-air within the annular space 25. It will therefore be clear that the heat accumulated by the bottom wall 16 30 of the partition 15 will be radiated downwardly on to the chicks within the hover.

Normally the sheet metal bottom wall 16 of partition 15 may be seated upon the top of the radiator 8 in which case heat will be transmitted 35 directly from the radiator to said bottom wall from which latter it will be radiated downwardly as described.

To the exterior of the canopy body 13 of the hover 9 are fastened the lower ends of a plurality 35 of cables 26 whose upper ends are fastened to one end of a single cable 27. This cable 27 extends upwardly over a pulley 28 and may be secured, when necessary, to a cleat 29 provided on the wall 4.

40 When it is desired to clean the floor of the hover the canopy body 13 of the latter is raised by pulling upon the cable 27 and is secured in an elevated position by fastening the said cable to the cleat 29. It will be clear that all of the 45 floor of the hover is easily accessible for the purpose of cleaning and replenishing the litter 30 with which the floors of hovers are ordinarily covered.

With most brooders as heretofore constructed 50 it has been necessary to cover the floor of the hover with a thick layer of dried peat in order to shield the chicks from the cold unheated floor. One feature of my invention utilizes the return conduit to heat the floor of the hover throughout 55 its extent in a very efficient manner so that it is unnecessary to employ the thick layer of dried peat heretofore required so that a thin sprinkling or layer of sand (not shown) will suffice.

In order to thus heat the entire floor of the 60 hover said floor has completely embedded therein a radiator, indicated generally at 31, which constitutes part of the return conduit 12. As herein shown this radiator 31 comprises two end manifolds 32 and 32a made up of pipe sections 65 and pipe fittings which are connected by a plurality of parallel pipe lengths 33.

The manifold 32 is made at its middle with a cross fitting 34 having three outlets and a single inlet that is connected with the outlet of the 70 radiator 5, while the manifold 32a is constructed at its middle with a similar cross fitting having three inlets and a single outlet that is connected with the inlet of the heater 11. Thus the hot water flowing by gravity away from the radiator 75 5 divides at the cross fitting 34 and passes through

all of the pipe sections 33 on its way to the heater 11.

The radiator 31 is made sufficiently large to heat the whole of the floor of the hover and in order to confine all of the heat given off by the radiator 31 to the top portion of the floor of the hover I arrange a blanket 36 of heat insulating material, such as asbestos, beneath the radiator 31. This blanket 36 prevents transmission of the heat downwardly into the lower part of the floor 10 or into the ground.

The floor 1 is preferably made from concrete and practically all of the return conduit including the radiator 31 is embedded and enclosed within the material of the floor so that the heat 15 from said return conduit is transmitted directly to the concrete of the floor and particularly to that part of the latter that is immediately adjacent and above the radiator 31.

In the return conduit, between the radiators 20 5 and 31, I provide a shut-off valve 37, and between this valve 37 and radiator 5 is provided a pipe union 38. In the supply conduit, between 25 radiator 5 and the heater 11, I provide another shut-off valve 39 between which and the radiator 5 is a second union 40. It will therefore be clear that by closing the two valves 37 and 39 and disconnecting the unions 38 and 40 the radiator 5 may be quickly removed when this is necessary without requiring any other adjustment 30 or alteration in the system.

Where a plurality of hovers are arranged within one and the same building they are usually disposed in a row and the supply conduit 10 as well as the return conduit 12 will be common to 35 all the hovers and will be connected with each as above described.

In practice, the upper horizontal portion of the supply conduit 10 is installed with a pitch 40 of one-half an inch to ten feet, the highest point being at the boiler or heater end thereof, while the return conduit 12 is installed with a pitch of about one-half an inch to ten feet and with the lowest point adjacent the boiler or heater 11. This eliminates the necessity of letting air out 45 of the radiators daily and the water flows more freely thus affording economy of fuel.

The arrangement of the return conduit within, and below the top surface of, the floor 1 obviates the use of a thick layer of litter 30 so that 50 a small amount of sand sprinkled thereon will suffice, thus reducing the labor involved in cleaning and preparing the floor, as well as the cost of materials. Also by embedding the return pipe with its radiator, or radiators, 31 within the material of the floor the use of platforms raised above the level of the floor which are unhandy to clean is avoided. It is also an advantage that the heat derived through the floor of the hover affords a saving in the amount of fuel consumed 60 and also a saving of fuel is secured through the use of the insulating blanket 36.

The above described construction of the partition 15 prevents loss of heat upwardly and reflects all of the latter downwardly on to the chicks 65 within the hover.

An advantage resides in the upright disposition of the radiator 5, and this advantage is that the radiator disposed in this fashion it is possible to completely clean all of the floor of the hover 70 from a standing position, whereas in other systems where the radiator is disposed horizontally it is necessary to get down on to the floor in order to clean under said radiator.

While the chicks are very small the hover may 75

be supported entirely by the radiator 5 but as the chicks grow the hover can be adjusted upwardly from time to time by means of the cable 27, if necessary.

5 What I claim is:—

A brooder house for chicks, said house being constructed with a concrete floor and having, in combination, a hover within said house comprising a conical sheet metal canopy body constructed intermediate the upper and lower ends thereof with a horizontal sheet metal partition wall having a central aperture communicating with the lower end of an imperforate flue which extends upwardly through the top of the sheet metal body and which is fixedly connected with the latter, said horizontal partition wall being otherwise imperforate; damper mechanism for controlling the flow of air through said flue; an upright radiator within said hover and resting upon said floor upon the top of which radiator said horizontal

partition wall rests flatwise so as to have substantial heat transmitting contact therewith; a supply conduit separably connected with the inlet of said radiator, a return conduit separably connected with the outlet of said radiator; a second horizontally disposed radiator structure constituting a part of said return conduit, said horizontally disposed radiator structure being completely embedded within the concrete of the floor directly beneath said hover and radiator and closely adjacent to the top surface of said floor; means supporting said hover so that it can be adjusted vertically toward and from said floor and fixed in adjusted position, and a blanket of heat insulating material that is also completely embedded within the concrete of said floor directly beneath and closely adjacent to said last mentioned radiator structure.

FRANK P. CRANDON. 20
